US0D1111625S

(12) **United States Design Patent** (10) **Patent No.:** **US D1,111,625 S**
(45) **Date of Patent:** **** Feb. 10, 2026**

(54) **DRINKING STRAW**

(71) Applicant: **Hongzhan Li**, Kaifeng (CN)

(72) Inventor: **Hongzhan Li**, Kaifeng (CN)

(**) Term: **15 Years**

(21) Appl. No.: **29/945,520**

(22) Filed: **Jun. 4, 2024**

(51) **LOC (15) Cl.** **07-06**

(52) **U.S. Cl.**

USPC **D7/300.2**

(58) **Field of Classification Search**

USPC D7/300.2, 397; D25/119, 122; D24/222,
D24/224

CPC A47G 21/18

See application file for complete search history.

Primary Examiner — S. Bryan Reinholdt, Jr.

(74) Attorney, Agent, or Firm — JEEN IP LAW, LLC

(57) **CLAIM**

The ornamental design for a drinking straw, as shown and described.

DESCRIPTION

FIG. 1 is a front, right and top perspective view of a drinking straw, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof; and,

FIG. 8 is an enlarged bottom plan view thereof.
